UNITED STATES PATENT OFFICE.

ABRAHAM NOVICK, OF NEW YORK, N. Y., ASSIGNOR TO UNITED STATES ENVELOPE COMPANY, OF SPRINGFIELD, MASSACHUSETTS, A CORPORATION OF MAINE.

MACHINE FOR MAKING WINDOW ENVELOPES.

Application filed March 31, 1921. Serial No. 457,377.

To all whom it may concern:

Be it known that I, ABRAHAM NOVICK, a citizen of the United States, and a resident of the city of New York, county of Kings, 5 and State of New York, have invented certain new and useful Improvements in a Machine for Making Window Envelopes, of which the following, together with the accompanying drawings, is a specification.

10 The present invention relates to a machine for making window envelopes, the latter being the type of envelope which provides an opening, usually covered by a transparent patch, in the face thereof, so 15 as to reveal the address on the enclosure.

The invention resides in a novel combination and arrangement of elements which are designed to facilitate, and render more secure, the application to the successive envelope blanks in process of manufacture, of the transparent patches or window coverings, all as more fully set forth in the following description, reference being had to the accompanying drawings, in which—

20 Fig. 1 is a side elevation of a window envelope machine embodying the improvements, with a part of the upper machine frame broken away.

Fig. 2 is a front elevation of said machine.

30 Fig. 3 is an enlarged sectional view of the patch applying mechanism, the section being taken on the line 3—3 of Fig. 5.

Fig. 4 is a view similar to Fig. 3, the section being taken on the line 4—4 of Fig. 35 5, and showing the patch applying mechanism in a different position.

Fig. 5 is a front elevation of the mechanism shown in Figs. 3 and 4.

40 Fig. 6 is a horizontal sectional view on the line 6—6 of Fig. 5.

Fig. 7 is a horizontal sectional view on the line 7—7 of Fig. 1.

Fig. 8 is a fragmentary detail view showing a typical cam movement in the machine.

45 Fig. 9 is a plan view of one of the envelope blanks, illustrating the application of moist gum thereto, preparatory to the application of a transparent patch.

50 Like reference characters refer to like parts in the different figures.

The fixed framework of the machine provides vertical slideways 1, 1 for a blank table or support 2, the latter adapted to sustain a pile or stack of blanks 3 which 55 may be of the shape and configuration

shown in Fig. 9, or any other desired shape. Said blanks are adapted to be removed, one by one, from the top of the stack 3, and in common with machines of the same class, the machine of the present invention provides suitable elevating mechanism, operated automatically, for procuring an upward feed for the table 2, in order to maintain the top of the stack 3 in position to be operated upon by the blank removing means, as hereinafter described. Said automatic elevating mechanism, of any well known type, is not specifically shown or described herein, since it forms no part of the present invention.

The successive topmost blanks of the stack 3 are operated upon by a suitably constructed gumming and picking device 4, the latter being carried by a rod 5 which travels in brackets 6, and being actuated by a cam 7 on the main shaft *a* of the machine. Said cam 7 operates a push rod 8, the latter being connected to a lever 9 on a rock shaft 10 which provides a link connection 11 with the rod 5. The reciprocating gumming and picking device 4 presents a plurality of suitably disposed gumming dies on its under surface, so arranged as to contact with the blank, along its edges, and around the cut-out window thereof, in the manner indicated by the shaded areas on Fig. 9. For applying adhesive to the dies of gumming and picking device 4, the machine provides a travelling gum roll 12, which, at one end of its movement, makes contact with and receives gum from a suitable gum transferring roller 13, the same being mounted in a gum box 14, of ordinary construction. The supports 15 of the travelling roller 12 move back and forth on horizontal rods 16, in order to bring the travelling roller in contact with the dies on the bottom of device 4, when the latter is in raised position; to this end, any suitable means may be employed for reciprocating the supports 15, as for instance, the links 17, 17, connected to bell cranks 18, 18 and actuated from the main shaft by the typical cam and push rod arrangement which is shown in Fig. 8.

100 The contact of the gummed surfaces of reciprocating picking device 4 with the topmost blank of the stack 3 causes the separation and elevation of said blank on the upward movement of device 4, the blank being 105 110

brought in the usual manner against stationary stripping plate 19, which provides suitable apertures 19' for the passage of the dies of device 4. This contact with the under side of plate 19 strips the blank from the picker 4, and coincidentally, said freed blank is engaged edgewise by hooked fingers 21, 21 on the ends of reciprocating arms 20, 20. The arms 20 are moved horizontally 10 back and forth in suitable guideways by means of links 22, pivotally connected to a bell crank 23 which is operated through a rod 24 from an eccentric 25 on the main shaft *a*. The return movement of the arms 15 20 is such as to carry the gummed blank partly across the creasing plate 26 of the machine, as indicated in Figs. 3 and 4, the advancing edge of said blank being squared and registered by contact with a pair of stop 20 fingers 27, so disposed that the cut-out window portion of the blank is superposed upon a ledge or extension 28 which lies adjacent to the rectangular aperture 29 of creasing plate 26. 30 A blank thus brought to rest upon the creasing plate 26, and rearwardly of the position which it occupies when acted upon by the usual creasing plunger, is in readiness for the application of the transparent patch thereto; the window aperture of the blank, with its margin of moist gum, is superposed upon the firm support provided by extension 28. As herein shown, the transparent patch material is taken from a 35 roll 30, and is fed by means of automatically operated feed rollers 31, 31, the latter being geared together for rotation in unison, by means of gears 31', one of which is shown in Fig. 7. For operation of the rollers 31, 40 31, the machine provides a sprocket chain 32 connecting the sprocket 33 on the main shaft *a* with a sprocket 34 on a shaft 35. Gears 36 and 37 transmit rotation of shaft 35 to the shaft of upper feed roller 31. 45 The web of patch material is projected by the feed rollers 31, 31 between suitable guide devices 38, 38, the latter directing the material to the cutting mechanism which comprises stationary and movable knife 50 edges 39 and 40. The action of this mechanism is as follows:—Patch material is projected downwardly and forwardly past the cooperating knife edges so that its free end covers the surface of pivoted hollow member 41, which provides a plurality of suction 55 openings 42. The latter, communicating with the interior of said member, are connected by a passage 43 to a hollow trunnion shaft 44, by which said member 41 is supported. The trunnion shaft 44 is connected by means of a flexible tube 45, Fig. 7, to a vacuum pump 46, Fig. 2, the latter being operated by any suitable cam and push rod arrangement from the main shaft *a*, such as 60 65 the arrangement shown in Fig. 8. The

operation of pump 46 is so timed as to create a partial vacuum in the member 41 coincident with the arrival of the patch material in position to be acted upon by the suction holes 42; thereupon, with the patch material held firmly in place by the vacuum, the knife edge 40 is operated to sever the web, and to provide a single patch of the requisite width for application to the gummed window opening. The knife edge 70 75 40 is actuated by a cam 47 on shaft 35, which works against a roller 48 that is carried by an arm 49 on a shaft 50. The arm 51, projecting downwardly from the shaft 50, is suitably connected to the knife edge 40 to actuate the same when said shaft 50 is rocked, said arm being acted upon by a spring 52 which maintains the roller 48 against the cam 47.

Upon the severance of the individual patch from the web of material as above described, the member 41, against which said patch is held by vacuum, is adapted to be rocked or swung about its hollow trunnion 44, so as to carry the patch face downward into contact with the gummed window aperture of the blank at rest on the extension 28. This swinging motion of the member 41 is accomplished by a cam 53, on shaft 35, said cam acting upon a roller 54 on the end of an arm 55 which is carried by a shaft 56. The shaft 56 carries a suitable bell crank lever 57, one arm of which is connected by a spring 58 to the fixed framework, while the other arm provides a segmental toothed rack 59 that meshes with a similar rack 60 on the trunnion shaft 44 of member 41. In this way the intermittent oscillation of the member 41 is effected, and it will be understood that when said member arrives at the position indicated in Fig. 4, the suction therethrough is automatically broken or cut off, by any suitable means provided for this purpose. In consequence of this, the return of said member to its normal position, as indicated in Fig. 3, leaves the patch, by adhesion, in contact with the gummed surface of the blank, and covering the window aperture therein. 100 105 110

With the patch thus applied, the blank is in condition for the usual creasing and folding operations, but before these operations are commenced, said blank must be moved outwardly on the creasing plate 26 so as to bring its several lines of fold, indicated by dotted lines in Fig. 9, into registry with the edges of the rectangular opening 29 of said creasing plate. This reverse movement of the blank is accomplished on the next ensuing outward stroke of the arms 20, 20 as they are moved again into position to receive the next blank that is stripped off of the picker device 4. To supplement the action of arms 20, 20, the normally fixed stops 27, 27, against which the edge of the 115 120 125 130

blank has been previously projected, are moved in unison therewith until the blank has registered properly with the opening 29. Such movement of the stops 27, 27 is effected by means of a bell crank lever 61 which is connected by links 62 to a pair of sliding fingers on which said stops 27 are formed. The lever 61 is pivoted at 64, and its other arm carries a roller 65 which makes contact with a cam 66 on a shaft 67, Fig. 1. The shaft 67 constitutes the rocking pivot of lever 23, and consequently insures the movement of stops 27 for a part of the stroke of arms 20, 20, there being no movement of said stops 27 when the concentric portion of the cam 66 is in contact with roller 65.

In this way, the blank with the patch applied thereto, as above described, is carried back the requisite distance so as to register correctly with the rectangular opening 29 of creasing plate 26. Thereupon, as the arms 20 and hook fingers 21 continue their outward movement, on the way to the seizure of the next blank, the creasing plunger 68 descends, and forces the patched blank lying on the creasing plate through the opening 29 and against the bottom of the usual folding box 69. The plunger 68 is carried by rod 70 and is reciprocated in the usual manner by means of levers 71 and 72, the latter being pivoted at 73 and operated by a push rod 74 which is driven from the main shaft by the typical cam arrangement shown in Fig. 8.

In the folding box 69 the creased blank is seized by suction exerted through holes 75 in the bottom 69' thereof, these holes communicating with a vacuum chamber 76 that is connected by tubing 77 to an air pump 78. The usual side flap folders 79, 79 and the seal and bottom flap folders 80, 81 function in the ordinary way to turn down the upturned flaps of the blank, being actuated by links and rods 82 and 82' that derive motion from the typical cam arrangement shown in Fig. 8. The completed envelopes are discharged from the folding box by the downward movement of its bottom 69', swinging about the pivot 83. At this moment, the air suction in the chamber 76 is released, to permit the completed envelope to drop by gravity into one of the compartments of a chain drier 84, the latter delivering suc-

sive formed envelopes upon a platform 85 which, in the usual way, transfers them to the delivery table 86 of the machine. 55

I claim,

1. The combination with the apertured creasing plate of an envelope machine, of means for conveying successive apertured blanks thereto, means for pressing a transparent patch onto each blank, to cover the aperture therein, while said blank is resting on said creasing plate, and means for thereafter reversing the movement of each blank to register it with the aperture in said creasing plate. 60

2. In an envelope machine, the combination with the usual apertured creasing plate and creasing plunger, of a patch applying and pressing mechanism constituted in part by an extension of said plate, means for first subjecting apertured blanks to the action of said patch applying and pressing mechanism, and means for thereafter reversing the movement of each blank to register it with the aperture in said creasing plate and with said plunger. 70

3. In an envelope machine, the combination with the usual apertured creasing plate and creasing plunger, of a patch applying and pressing mechanism, and a reciprocating blank conveying means adapted by movement in one direction to subject each blank to the action of said patch applying and pressing mechanism, and adapted by movement in the other direction to register each patched blank with the aperture in said creasing plate and with said plunger. 80

4. In a machine for making window envelopes, the combination with picking mechanism for applying adhesive to the flaps and window margin of a blank, and creasing and folding mechanisms for said blank, of a patch applying mechanism in line with the movement of said blank from said picking mechanism to said creasing and folding mechanisms, said patch applying mechanism being operable on said blank beyond said creasing and folding mechanisms. 90

Dated March 19, 1921.

ABRAHAM NOVICK.
